UNITED STATES PATENT OFFICE.

KENZAEMON NISHIMOTO, OF OAKLAND, CALIFORNIA.

SOAP-BOX.

No. 853,824.

Specification of Letters Patent.

Patented May 14, 1907.

Application filed June 25, 1906. Serial No. 323,302.

To all whom it may concern:

Be it known that I, KENZAEMON NISHIMOTO, a citizen of the United States, residing at Oakland, in the county of Alameda and State of California, have invented new and useful Improvements in Soap-Boxes, of which the following is a specification.

My invention relates to boxes for holding toilet-soap.

10 The invention consists of the parts and the construction and combination of parts as hereinafter more fully described and claimed, having reference to the accompanying drawings, in which—

15 Figure 1 is an end elevation of the invention open for use. Fig. 2 is an end elevation of the same in closed position. Fig. 3 is a plan view of the box opened out. Fig. 4 is a plan view of the box closed with the cover 20 partly broken away.

My box is made in three sections A B C: A dish or tray section A, and two complementary cover sections B C hinged to opposite sides of the tray section as at 2 and foldable 25 outward and downward as in Fig. 1 to provide legs for the section A or to be closed cover fashion and locked as in Fig. 2. The sections B C are each open on two sides so as to close over the cake of soap 3 and protect it 30 when the box is not in use.

4 represents a flexible elastic foraminous false bottom on which the soap is supported out of contact with the tray when the box is opened out for use as in Fig. 1. This false bottom 4 is of any suitable form or material. 35 As here shown it consists of a coil spring suitably connected to the cover sections B C as at 5 so as to be removable; said spring being normally expandible beyond the width of the 40 tray, but not to exceed the length of the latter as indicated in Fig. 3.

The hinges 2 of the cover sections B C are arranged on the opposite top edges of the tray section A, and the connections 5 for the elastic soap support 4 are arranged as high as is 45 convenient above the bottom of the tray when the cover sections are opened, so as to maintain the soap out of contact with the bottom of the tray when the box is in use.

When the box is closed, the spring is compressed and assumes the position as shown in Figs. 4 and 2. When the box is open for use, the expansive action of the spring acting through its connections 5 above the hinges 2, as in Fig. 1, aids in keeping the cover sections 55 in rigid position so that the tray is supported as on legs.

The several sections are held in closed position by suitable locking means as the concavities 7 in the spring sides of the sections B C 60 engaging corresponding protuberances or convexities 8 in the spring ends of the tray A when the parts are folded up. To open the box, it is only necessary to press in on the convexities 9 on the ends of the tray section 65 which releases the covers and they fly open of their own accord.

Having thus described my invention, what I claim and desire to secure by Letters Patent is—

1. A soap box comprising a tray section for supporting the cake of soap and two complementary cover sections, said cover sections being hinged at their lower portions to the outer portions of the tray section and being 75 adapted to fold outwardly and downwardly below the tray section to form supporting legs for said tray section.

2. A soap-box comprising a tray section, two complementary cover sections hinged to 80 said tray section and opening outwardly and downwardly relative thereto, and an elastic false bottom secured to the cover sections and supported out of contact with the bottom of the tray section, when the box is open 85 for use.

3. A soap-box comprising a tray section, two complementary cover sections, hinged to 90 said tray section and opening outwardly and downwardly relative thereto, an expandible spring bottom secured to and bearing against the cover sections to hold the latter in open position, and means to hold the cover sections closed in opposition to the action of said spring bottom.

4. A soap box comprising a tray section, cover sections hinged at their lower portions to the tray section, and an expansible false

bottom normally of greater width than the tray section and having its sides engaging the cover sections proximate to the hinged points of the latter, whereby the expansive action of 5 said false bottom maintains the cover sections in a substantially rigid open position.

In testimony whereof I have hereunto set

my hand in presence of two subscribing witnesses.

KENZAEMON NISHIMOTO.
